UNITED STATES PATENT OFFICE.

BENJAMIN W. TANZY, OF DETROIT, MICHIGAN.

HOSIERY SHIELD.

Application filed November 26, 1926. Serial No. 150,937.

This invention relates to shields especially intended for the protection of women's hosiery from mud-splashes thrown backward and upon the upper central portion of the hosiery by the shoe-heels in walking in rainy or slushy weather.

The object and purpose of my invention is to provide a hosiery shield that is light in weight and compact in size so as to permit being readily folded and carried in a lady's hand-bag or pocket-book convenient for emergency.

Another object is to provide a hosiery shield that is neat and attractive in appearance, durable in service, easily and quickly attached to the limb of a person to which it also affords protection.

A further object and purpose is to provide a shield for hosiery of transparent water-proof material, through which the hosiery and color thereof are visible.

These objects and purposes of my invention are attained by the simple construction of the device illustrated in the accompanying drawings in which similar numerals and letters of reference refer to and indicate like parts throughout the several views.

Referring to the accompanying drawings forming a part of this specification, Figure 1 illustrates a side view of the hosiery shield attached to a limb of a person; Figure 2 is a view similar to Fig. 1, showing the lower strap 8 modified and enlarged to cover and protect the instep of a foot where low cut oxford shoes are worn; and Figure 3 is a perspective view of the device, shown detached.

Described more fully and in detail, referring to Figs. 1, 2, and 3, the construction of my device comprises a shield member 1, which 40 may be made of suitable water-proof material, rubber, fabric, preferably, transparent oil-silk, and suitably fashioned to fit and snugly conform to the lower portion of the limb of a person between the knee and ankle, 45 and adapted to be worn over and cover the back portion of the hosiery A, which is rendered visible through the transparent sides 2 thereof.

The lower forward open portion of the shield member 1 is provided with a detachable instep shield member 8 made of similar material as the first member, which is provided to cover and shield the front portion of the hosiery and limb of the wearer at, below and 55 above the instep when a low-cut or oxford

shoe is worn, both shield members having their bottom portions adapted to cover snugly the outside of the top thereof, shown illustrated in Fig. 2.

The detachable instep shield member 8 is 60 provided with fasteners 9 on its sides or ends, which are adapted to engage or interlock with fasteners 6 provided on the lower outside portion of the shield member 1, approximately at or over the ankle part thereof when detachably secured on the limb of a person, illustrated in Fig. 2; or a strap 4 provided with fasteners 6 on its ends adapted to engage or interlock with the fasteners 6 provided on the lower open sides of the shield member 1 may 70 be employed for this purpose, illustrated in Figs. 1 and 3.

The forward open sides of the rear shield member 1 are provided with a flexible friction piece 7 secured in a suitable manner 75 thereto, and employed to overcome the tendency of said sides to crumple and also to aid them in conforming more snugly to the shape of the limb of the wearer when walking. However, these sides may be made to fold or 80 lap over and secured as a binding or friction piece to answer the same purpose without departing from the spirit of my invention.

The detachable instep shield member 8, 85 illustrated in Fig. 2, is an enlarged modification of the strap or band 4, illustrated in Figs. 1 and 3, and is provided to cover and shield the entire instep and ankles of the wearer, which are usually exposed when low-top shoes are worn.

Having thus described my invention, what I claim is:

1. A hosiery shield of the character described, comprising a shield member constructed of waterproof material suitably 95 fashioned and adapted to be worn over and snugly cover approximately the rear half portion of the hosiery on the limb of a person, an instep shield member made of similar material as the first shield member, suitably 100 fashioned and adapted to be worn over and shield approximately the front portion of the hosiery on the limb of the wearer at, below and above the instep thereof, means for detachably fastening the said shield members 105 to each other, and means for securing the same on the limb of the wearer.

2. A hosiery shield of the character described, embodying a shield member constructed of waterproof material, suitably 110

fashioned and adapted to be worn over and snugly cover approximately the rear half portion of the hosiery on the limb of a person, an instep shield member made of like material as the first shield member, and suitably fashioned and also adapted to be snugly worn over and shield approximately the front portion of the hosiery on the limb of a wearer at, below and above the instep and ankles thereof, means for detachably securing the said shield members to each other, and means for detachably securing the said members on the limb of the wearer.

3. A shield for the protection of hosiery and limbs of the wearer of the character described, embodying a shield member constructed of visible transparent waterproof material suitably fashioned to snugly conform to, and adapted to be worn over approximately the rear half portion of the hosiery on the limb of the wearer, and adapted also to render the said hosiery and the color thereof visibly exposed therethrough; an instep shield member made of like material as the first rear shield member, suitably fashioned and adapted to be worn over and to shield approximately the front portion of the hosiery on the limb of the wearer at, below and above the instep and ankles thereof, means for detachably fastening the said rear and front shield members to each other, and means for detachably securing the said shield members on the limb of the wearer.

4. A hosiery shield, comprising a shield member constructed of waterproof material, suitably fashioned and adapted to be worn over and to cover approximately the rear half portion of the hosiery on the limb of a person,

an instep shield member made of similar material as the first rear shield member, also suitably fashioned and adapted to be worn over and shield approximately the front portion of the hosiery on the limb of the wearer at, below and above the instep and ankles thereof, means for detachably securing the said instep shield member to the rear shield member, means for securing both of said shield members to the limb of the wearer, and means for decreasing any tendency of the said sides of the rear shield member to crumple on the limb of the wearer when walking.

5. A visible shield for the protection of hosiery and limb of the wearer, embodying a shield member constructed of transparent waterproof material, suitably fashioned to snugly conform to the limb of a person, and adapted to be worn over the hosiery thereon and covering approximately the rear half portion thereof, and also to render the said hosiery and color thereof visibly exposed therethrough; an instep shield member constructed of similar material as the first said rear shield member, and suitably fashioned and adapted to snugly conform to, and worn over, to shield approximately the forward portion of the hosiery on the limb of the wearer at, below and above the instep and ankles thereof, means for detachably securing the said instep shield member to the said rear shield member, means for detachably securing both of said shield members on the limb of a person, and means for reinforcing the sides of the rear shield member to decrease any tendency thereof to crumple on the limb of the wearer when walking.

BENJMAN W. TANZY.
